UNITED STATES PATENT OFFICE.

HERMANN TONN, OF CHICAGO, ILLINOIS.

METAL BELT-LACING.

1,151,979.

Specification of Letters Patent. Patented Aug. 31, 1915.

Application filed January 10, 1914. Serial No. 811,339.

To all whom it may concern:

Be it known that I, HERMANN TONN, a citizen of the United States, residing in the city of Chicago, county of Cook, and State 5 of Illinois, have invented certain new and useful Improvements in Metal Belt-Lacing, of which the following is a specification.

The object of my invention is to provide a belt lacing which is at once simple, effective, 10 durable, inexpensive and easy to apply.

In the drawings, Figure 1. is a perspective view of a piece of my improved belt lacing in its preferred form as it appears before it is applied to a belt; Fig. 2. is a top 15 plan view of the lacing shown in Fig. 1.; Fig. 3 is a side elevation of such lacing; Fig. 4 is a side-elevation of such lacing applied to a belt; Fig. 5 is a top plan view of the lacing and belt shown in Fig. 4; Fig. 6 is a 20 bottom view of the lacing and belt shown in Fig. 4; Fig. 7 is a side elevation of a modified form of my lacing, used especially in the case of round belts; Fig. 8 is a sectional elevation, along line 8—8 in Fig. 7, of the lacing 25 shown in Fig. 7; Fig. 9 is a side elevation of such lacing applied to a belt; and Fig. 10 is a perspective view of the lacing shown in Fig. 7, provided with a modified form of hooks.

Referring to the drawings, my lacing consists 30 preferably of a metal stamping, formed, as shown in Figs. 1 to 3, of a central plate 20 with hooks 21 thereto attached. These hooks are bent over from both the upper and 35 lower edges of plate 20, alternately projecting to the right and to the left from each edge, and preferably arranged so that for each hook bent over to one side, another hook is bent over to the opposite side, in the 40 same vertical plane, from the opposite edge of plate 20. Hooks 21 are bent so as to leave open, between their points, openings 45 into which ends 23 of belt 24 may be projected so as to be brought in contact, from opposite sides, with plate 20. When this has been done, hooks 21 may readily be hammered or pressed into ends 23, thereby 50 fastening them together as shown in Figs. 4 to 6. The shanks of the upper and lower hooks, respectively, on each side of plate 20

are preferably made of different length in order that the points of the hooks may not all penetrate ends 23 at the same distance from plate 20.

The form of lacing shown in Figs. 7 to 9, 55 used especially with round belts, has the special advantage that it may easily be made so as to grip the belt ends from three, four, or more sides. Its central plate 20 is preferably made round, and of slightly smaller 60 diameter than the belt on which it is to be used, and hooks 29 project from it alternately to one side and to the other, in such manner that each of the belt ends may be engaged by two, three or more hooks 29 65 driven into it from substantially opposite directions. The lacing illustrated by Fig. 10 is substantially the same as that shown in Figs. 7 to 9, except that the hooks are formed in a different way, and that each 70 prong is provided with two hooks. This form of hooks is of particular advantage with round belts because it is difficult to drive single hooks straight into a round belt. 75

Further modifications of my lacing may easily be conceived. All such are intended to be covered, if within the purview of my claims.

I claim:

1. As a new article of manufacture, a metal belt lacing comprising a plate adapted to be interposed between the belt ends to be joined together so as to face the butts of such belt ends with its flat surfaces, and 85 hooks integral with said flat plate and projecting therefrom in opposite directions so as to be adapted to grip both of said belt ends by being driven into them from substantially opposite directions. 90

2. As a new article of manufacture, a metal belt lacing comprising a plate, adapted to be interposed between the belt ends to be joined together so as to face the butts of such belt ends with its flat surfaces, and 95 hooks projecting from the edges of such plate alternately to one side and to the other, and adapted to grip an end of a belt on each side of the plate by being driven into it. 100

3. As a new article of manufacture, a metal belt lacing comprising a connecting body, and hooks projecting from such body in opposite directions so as to be adapted to grip both ends of a belt from substantially opposite directions, each of said hooks being

provided with two prongs adapted to enter said belt side by side.

HERMANN TONN.
